Arthur C. Jermyn, 240 Danbury Circle N.,
Rochester 18, N.Y.

Filed May 19, 1964, Ser. No. 80,056

Term of patent 7 years

(Cl. D86—10)

FIG. 1

FIG. 2

FIG. 3

FIG. 4

FIG. 5

FIG. 1 is a plan view of a comb tray, showing my new design in which the bottom of the tray is provided with an array of openings having a similar geometric shape and in which the portion of the array to the right of the second group of vertically disposed holders is continuous throughout the portion of the bottom shown as being broken away;

FIG. 2 is a side elevational view of the comb tray, shown in FIG. 1;

FIGS. 3 and 4 are end elevational views of the left and right ends, respectively, of the comb tray shown in FIG. 1; and

FIG. 5 is a plan view of a comb tray, similar to that shown in FIG. 1 in which the bottom of the tray is provided with an array of geometric openings between the vertically disposed holders and to the right of the second group of holders that have a different geometric shape than those shown in FIG. 1 and in which the portion of the array to the right of said holders is continuous

throughout the portion of the bottom shown as being broken away.

I claim:

The ornamental design for a comb tray, substantially as shown and described.
